Inventor:

Hattie Fels,
By her Attorney,
Leo. F. Niath

UNITED STATES PATENT OFFICE.

HATTIE FELS, OF NEW YORK, N. Y.

GARMENT.

1,414,349.

Specification of Letters Patent.

Patented May 2, 1922.

Application filed December 5, 1921. Serial No. 519,959.

To all whom it may concern:

Be it known that I, HATTIE FELS, a citizen of the United States, and a resident of the borough of Manhattan, city, county, and State of New York, have invented certain new and useful Improvements in Garments, of which the following is a specification.

My improvements relate to outer garments of the overall type, being adaptable for general use in that respect, both for adults and juveniles, having for its object among others to provide a garment embodying an upper portion and a lower bifurcated portion with a flap at the upper edge of which is provided an elastic band, there being means for attachment of the flap to the upper portion to provide for vertical adjustment in accordance with the height of the wearer.

In the accompanying drawings,

Fig. 1, is a rear perspective of the garment, with one corner of the back flap opened up in part;

Fig. 2, is a front perspective of the garment;

Fig. 3, is a detail of a portion of the constrictive rear waist band.

My "union" overall garment consists essentially of the frontal body or vest portion V, connected by shoulder straps s, s, with the back flap B, and formed with an enlarged vertically-disposed elongated opening, as seen in Figure 1, whereby the said portion forms sort of a sweater, permitting of ready application of the garment by slipping the head of the wearer through said opening, gaiter leggings L, L, being integral with the vest portion V, as indicated particularly in Fig. 2, and terminating in gaiters G, G, formed with the usual instep straps g, g, and with the plackets g', g', provided with suitable means of closure attachment, as for instance the snap buttons a, a, of the so-called "glove button" type, as indicated in the drawings, or any equivalent expedient.

Provision is made for detachably securing the upper rear portion, or drop flap D, forming the seat of the trousers, to the lower portion of the back flap B, by a suitable or well known means, as by suspender straps and buckles c, c', shown in Fig. 1. By this means there is provision for vertical adjustment of the upper portion

relatively to the lower portion to conform to the height of the wearer. Side plackets d, d, are also provided at the sides of the garment for detachably securing the drop flap D, to the upper front portion of the trousers L, L, snap buttons a', a', or equivalent means being used for the purpose.

The upper edge of the drop flap D, is formed with constrictive means which tend constantly to draw the waist portions of the garment taut and snug. For this purpose an elastic-resilient band e, may be inclosed in a casing e', formed by inturning the upper edge of said drop flap,—the ends of the constrictive band e, being of course secured at the sides of the drop flap D.

My unitary one piece outer garment or overall affords full and continuous protection for the body of the wearer, preventing gaps between upper and lower raiment, and effectually shielding the same from contact with extraneous objects. At the same time ample provision is made for convenient manipulation and attachment or detachment of the copulative parts, so that the garment may be donned or removed with facility.

What I claim as my invention and desire to secure by Letters Patent is,

1. As an improved article of manufacture, a garment comprising an upper portion having an enlarged vertically elongated opening and a bifurcated lower portion, the latter having a rear flap, straps and cooperating means on the flap and upper portion whereby the upper portion may be adjusted vertically in accordance with the height of the wearer.

2. As an improved article of manufacture, a garment comprising an upper portion with vertically-disposed enlarged elongated opening, and a bifurcated lower portion, the latter having a rear flap, an elastic band at the upper edge of the said flap, and straps and cooperating means on the flap and upper portion whereby the upper portion may be adjusted vertically relatively to the lower portion in accordance with the height of the wearer.

HATTIE FELS.
